(57) **CLAIM**

The ornamental design for a mobile terminal display screen with graphical user interface, as shown and described.

DESCRIPTION

FIG. 1 is a front elevation view of a mobile terminal display screen with graphical user interface according to a first embodiment;

FIG. 2 is a front elevation view of a mobile terminal display screen with graphical user interface according to a second embodiment;

FIG. 3 is a front elevation view of a mobile terminal display screen with graphical user interface according to a third embodiment;

FIG. 4 is a front elevation view of a mobile terminal display screen with graphical user interface according to a fourth embodiment; and,

FIG. 5 is a front elevation view of a mobile terminal display screen with graphical user interface according to a fifth embodiment.

The dashed lines represent unclaimed features that form no part of the claimed design. The long dash-short dash lines indicate the display boundary of the mobile terminal display screen.

1 Claim, 5 Drawing Sheets
